UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WINDOW-CONTROL MECHANISM.

Application filed April 12, 1926. Serial No. 101,466.

The invention relates to window controlling devices and has a particular application to control devices for the sliding windows of automobiles and other vehicles.

5 It is the object of the invention to provide an improved actuating means for windows of the "jump the fence" type, this type of window as is well known in the art being provided with a weather strip skirting the 10 lower edge of the sliding window member, which strip is engageable by a slight transverse shifting and by a subsequent slight downward shifting of the window member, with a fence rail carried by the bottom cross 15 strip of the window frame.

This application is a duplicate of the John D. Lawrence and Stanley W. Nicholson application, Serial No. 467,822, filed May 9, 1921, upon window control mechanism.

20 In the drawings:—

Figure 1 is an interior view of a motor vehicle door having a sliding window control in accordance with the invention, the 25 window being shown in a partially raised position;

Figure 2 is an enlarged view of the control mechanism adjusted to a position corresponding to the raised or closed position 30 of the window;

Figure 3 is a fragmentary vertical section showing in full lines the maximum raised position of the sash and in dash lines its slightly lowered closed position;

35 Figure 4 is a fragmentary horizontal section on the line 4—4 of Figure 2;

Figures 5 and 6 are views similar to Figure 2 disclosing modified constructions.

In these views the reference character A 40 designates a vehicle door having in its upper portion a window opening B, a closure for which is formed by a vertically sliding glass plate C which in lowered position enters the chamber D formed in the lower portion of said door. Vertical adjustment of the window member C is effected by a control arm E pivoted within the chamber D upon a bracket F. Said bracket is suspended some distance beneath the window opening B by a pair of spaced vertical rods G secured at their upper extremities to a bracket H which is mounted upon a lock board I. For actuation of the arm E a

handle J is mounted upon a shaft K journaled in the bracket H, said handle, which is the only portion of the mechanism not concealed within the chamber D, being upon the inside of the door, conveniently located for manipulation. A pair of worm gears 55 L establish a drive connection from the shaft K to the upper end of a vertical shaft M arranged preferably between the rods G and journaled at its upper and lower ends respectively in the brackets H and F. A driving connection is established from the lower end of the shaft M to the swinging arm E through a second pair of worm gears 60 N and N'.

The means shown for engaging the control arm E with the sliding glass plate C 70 comprises a roller O journaled upon the upper end of said arm and a sheet metal strip P attached to the bottom edge of the glass C and fashioned to form a laterally opened channel shaped retainer for the roller 75 O, said roller being adapted to travel in said retainer along the bottom edge of the glass when the same is being adjusted. The strip P is preferably engaged with the plate C by engaging the extremities P' and P² 80 of said strip respectively with the interior and interior faces of said plate. The exterior edge portion of said strip is hooked inwardly to provide a weather strip and said hook is engageable through the transverse movement of the window member C, 85 subsequent to raising thereof, with a fence rail Q secured to the bottom cross piece Q' of the window frame.

In Figure 3 there is disclosed in full lines 90 the initial positions of the sliding window member and control arm after said member has been raised, and in dash lines there is indicated the position assumed by said parts after the window member has been shifted 95 slightly outward and lowered slightly to engage the hook P² with the fence rail Q. The outward shifting of the window member C is automatically accomplished by a mechanism now to be described. R is a roller 100 journaled adjacent the outer end of the control arm E upon a pintle R', the ends of which are bent as illustrated in Figure 2 to mount said pintle upon the arm. Preferably a slot R² is formed in the arm to accommodate the roller. As said arm approaches

its uppermost limiting position, the roller R is adapted to engage a cam-way S mounted upon the lock board I and having its cam face forming an acute angle with the vertical face of the lock board as is best seen in Figure 4. As the roller R rides upon the inclined end of said cam member, the arm E is gradually sprung transverse to the plane of its normal rotation through a slight angle and the window member C, being constrained to follow the upper end of the control arm, is shifted outwardly by this movement of the arm so as to register the hook P² with the fence rail Q. (See dash-line illustration in Figure 4). The described outward actuation of the member C occurs during approach of the arm E to a vertical position. After registration of the hook P² with the fence rail Q, the arm E is further actuated, through a slight angle, to the limiting position shown in dash lines in Figure 2, whereby the window member is lowered sufficiently to engage the hook P² with the fence rail Q, as is shown in dash lines in Figure 3. Thus in the closed position of the window a weather seal is established jointly by the elements P² and Q effectively preventing access of moisture to the chamber D. To lower the window member C, the handle J is reversely rotated, imparting a counter clockwise rotation to the arm E. In the initial portion of this movement, said arm, traveling from the dash-line position shown in Figure 2 to its vertical position, actuates the window member C upwardly sufficiently to disengage the hook P² from the fence rail Q. Continued actuation of the arm E in the same direction then engages the roller R² with the cam-way S, and the arm E will spring back to its normal position, shifting the window member C inwardly to the position indicated in full lines in Figure 3, as said roller traverses the incline of said cam-way. Continued rotation of the handle J will then effect the desired lowering of the member C.

It is a feature of the described invention that the sliding window member is held locked in any position of adjustment by the worm gears N and N' which, as is well known, permit no reverse drive. A further desirable feature of the invention is the suspension of the control arm E and its supporting bracket F from the bracket H which is attached to the lock board, a unitary relation thus being established between the arm and its control mechanism, facilitating installation in a vehicle.

In order to minimize the muscular effort required to shift the window member, the weight of the latter may be substantially counterbalanced by some suitable means as for example the pivotal arm U engaging at its free end beneath the strip P and urged upwardly by a coil spring V.

In the modified construction shown in Figure 5, a bracket W having an arcuate cam-way W' at its upper end depends from the lock board, and at its lower end provides a bearing for a journal member W² to which a lifter arm W³ and an actuating handle W⁴ are secured. A roller W⁵ upon said arm contacts with said cam-way W' similarly to the construction first described.

The form of the invention shown in Figure 6 provides a bracket X depending from the lock board and having an arm X' at its lower end upon which the lifter arm X² is journaled. A vertical shaft X³ is journaled upon said bracket and is adapted to actuate the arm X² through a worm X⁴ and worm wheel X⁵. Said shaft is driven through spiral gears X⁶ from a shaft Y journaled transversely of the shaft X³ at the upper end of the bracket X and carrying an actuating handle Y'.

What I claim as my invention is:

1. In a window control mechanism, the combination with a vertically sliding window member, of a downwardly hooked weather strip skirting the lower edge of said member, a complementary stationary fence rail having an upwardly projecting edge portion for engagement by the hook of the first mentioned strip, a mechanism for actuating the window member vertically, including an element adapted to swing parallel to the path of travel of said window member and a stationary cam-way engageable by said element in the position of the latter corresponding to the raised position of the window member for shifting the window member transversely to register the hook of the first mentioned weather strip with said fence rail.

2. In a window control device, the combination with a vertically slidable window member, of a weather strip adjacent the lower edge of said window member having a downwardly projecting hook, a stationary fence rail for engagement with said hook in the raised position of the window member, a control mechanism for said window member including a pivotal arm adapted to lie beside said window member, and a stationary cam-way engageable by said arm in the raised position of the window member to shift the latter transversely to register said hook with said fence rail.

3. In a window control mechanism, the combination with a vertically sliding window member, of a pivotal control arm engaging at its free end with the lower edge portion of said window member, a bracket forming a mounting for said arm, a second bracket spaced above the first mentioned bracket, means including a rod for supporting the lower from the upper bracket, a shaft having its extremities journaled respectively in said brackets, a drive connection between

the lower end of said shaft and said arm, and an actuating means for said shaft carried by the upper bracket.

4. In a window control mechanism, the combination with a vertically sliding window member, of a mechanism for actuating said member vertically, and a cam-way engageable by an element of said mechanism for flexing said element and shifting the window member transversely in its raised position to establish a weather seal.

5. In a window control device, the combination with a vertically slidable window member and a control mechanism for said member including a pivotal arm adapted to swing parallel to the path of travel of said window member, of a stationary cam-way engageable by said arm in the raised position of the window member to shift the latter transversely to establish a weather seal.

6. In a window control device, the combination with a vertically slidable window member, of a control mechanism for said member including a resilient pivotal arm and a stationary cam-way engaged by said arm in the raised position of the window member to spring said arm out of its normal plane of rotation to thereby shift the window member transversely for establishment of a weather seal.

7. In a window control device, the combination with a vertically slidable window member and a control mechanism for said member including a pivotal arm, of a stationary cam-way having a portion inclined to the normal plane of rotation of said arm engageable by the arm as the latter approaches a vertical position to shift the window member laterally for initial establishment of a weather seal, said cam-way having a portion parallel to the plane of rotation of said arm engaged by the latter during a further rotation during which engagement establishment of the weather seal is completed.

8. In a window control mechanism, the combination with a vertically sliding window member, of a member having an opening adapted to be closed by said window member, control mechanism for said window member including a pivotal arm, an actuating connection between said arm and the window member comprising a projection upon the outer or free end of said arm, and a channel shaped retainer for said projection secured to the lower edge portion of the window member, and means engageable by said arm in approaching its position corresponding to the raised position of the window member for shifting said arm and window member transversely of the latter into sealing engagement with said first-mentioned member at the lower end of its opening.

9. In a window control mechanism, the combination with a vertically slidable window member, of a stationary fence rail adjacent the path of travel of said window member, actuating mechanism for the window member including a pivotal arm, means for actuating the window member from said arm comprising a projection upon the outer end of the arm, and a channel shaped retainer attached to the bottom edge of the window member, a roller carried by the outer portion of said arm, and a stationary cam-way engageable by said roller in the position of the arm substantially corresponding to the raised position of the window member for moving the portion of the arm carrying said roller transversely to the plane of its rotation to thereby shift said window member transversely into weather sealing engagement with said fence rail.

10. In a window control device, the combination with a vertically slidable window member and a control mechanism for said member including a pivotal arm adapted to swing parallel to the path of travel of said member, of means for actuating said arm in the raised position of said member to shift the latter transversely to establish a weather seal.

11. In a window control mechanism, the combination with a frame, a window slidably engaging said frame, a stationary member upon said frame and a pivotal arm having an integral portion connected to the window, of means for swinging said arm parallel to the path of travel of the window for actuating the same and moving the integral portion of said arm in another direction to effect connection between said arm and stationary member.

12. In a window control mechanism, the combination with a frame, of a window member slidably engaging said frame, a stationary member upon said frame, and actuating mechanism for said window member including a pivotal arm connected to said window member for actuating the latter upon swinging of the former parallel to the path of travel of said window member, said arm having a portion thereof movable transversely of the swinging movement for establishing a connection between said arm and stationary member.

In testimony whereof I affix my signature.

STANLEY W. NICHOLSON.
